UNITED STATES PATENT OFFICE.

ALEXANDER D. CLARKE, OF OMAHA, NEBRASKA.

CURRENT-WHEEL AND FLOAT THEREFOR.

SPECIFICATION forming part of Letters Patent No. 249,899, dated November 22, 1881.

Application filed April 18, 1881. (Model.)

To all whom it may concern:

Be it known that I, ALEXANDER D. CLARKE, of the city of Omaha, in the county of Douglas and State of Nebraska, have invented certain 5 new and useful Improvements in Current-Wheels and Floats Therefor, of which the following is a description, reference being had to the accompanying drawings, which form a part of this specification.

10 My invention relates to pumping apparatus for use in raising water from running streams, and is more especially designed for use in the mining regions for elevating the water to be used in washing ores and mineral-containing 15 earth.

The invention consists in the novel combination and construction of the several devices hereinafter described.

The accompanying drawings show, at Figures 1 and 6, opposite sides of my improved apparatus; at Figs. 2 and 7, bottom and top views, respectively, of the same; at Figs. 3 and 4, details of the current-wheel whereby the pump is actuated, Fig. 3 being a partial 25 vertical or edge view, illustrating the different positions of the vanes, and Fig. 4 a radial section; and at Fig. 5 a section of the raft for floating the wheel and pump upon the line xx , Fig. 1. Fig. 8 is a section of an end of one of 30 the air-holding pipes forming the float.

In the said drawings, A represents a raft composed of a frame-work, A', and several series of air-containing vessels, A², held in the frame-work and formed of stove-pipe lengths 35 closed at the ends by plugs a, of wood or otherwise, and rendered tight and rust-proof by a coating, a', of coal-tar or its equivalent. In many sections where lumber is scarce this will be found more economical than wood for floating the raft. I prefer that the raft be made 40 in two parts, united by braces or timbers B, or otherwise, so that an opening, B', will be left over the wheel, as that permits access to the wheel or its removal for repairs.

45 C is a horizontal current-wheel, placed immediately below the raft, with its shaft C' extending up above the same and provided with bearings at two points, one in one of the cross-timbers, B, and the other in a spider-like framing, C², above the raft, to keep it perfectly true 50 under the varying side strains to which it is

subjected. The wheel is made with open light frame-work, so the water may pass freely through it, such frame-work consisting of top and bottom peripheral bands, c, top and bottom hub-plates, c', upon the wheel-shaft, outer vertical braces, c², inner vertical braces, c³, upper radial arms, c⁴, serving as pivots for the swinging vanes C³, and extending from the upper hub-plate to the outer braces, c², and lower 60 radial arms, c⁵, extending from the lower hub-plate to outer braces, c². This frame-work, while it possesses all requisite strength, is very light and will offer but slight resistance to the current; but it may be made in other fashions 65 of open framing, if desired, and combined with the other parts of my apparatus. The paddles or vanes C³ of this wheel are hinged to the rods c⁴ by loose hinges c⁶, located near the upper edge of the paddles, so that said 70 paddles, unless supported in some way, will fall by their gravity into a vertical position against the vertical rods c². When in the vertical position the current strikes them squarely and against their entire surface, but in order 75 that they may not retard the wheel during that part of the revolution in which they are going against the current I raise the paddles while they are passing through that portion of their circuit by means of a slideway, D, supported 80 by arms d, which slide is located within the circle described by the ends of the paddles, so that the latter will ride upon the same, said slide being bent at the ends to render gradual and easy the closing of the vanes. When 85 closed by this slide the vanes lie horizontally and cut through instead of resisting the current.

In Fig. 3 there is illustrated at the right hand the vertical or working position, at the center 90 a partially-closed position, and at the left hand the closed position. Friction upon this slide will be very slight, as all of the parts are submerged.

At the outer end of the vanes are angling 95 flanges C⁴, for the purpose of holding the water which may be pressing against the vanes, so the full benefit of its motion may be obtained.

Above the raft the wheel-shaft carries a large 100 pulley, C⁵, a belt or chain, C⁶, from which transmits power to another pulley, E, mounted upon the shaft E' of a centrifugal-pump wheel lo-

cated below the raft in a casing, E², having holes *e* at the bottom, said shaft being provided with two bearings, one in the timber B below and the other in a tripod or spider-frame, 5 E³, above. The pipe E⁴ leads from the pump-chamber E² and conducts the pumped water away to the desired point.

The pump and the wheel are both removable by taking out the fastenings of the spider-10 frames above them and the cross-braces B, through which their shafts pass. These fastenings consist of the bolts G or any other suitable devices. When the frames and braces are taken away there is no obstacle to prevent 15 the wheel or pump being moved through the opening B' until their shafts have passed beyond such opening; or, if depth of water will permit, they may be tipped upon edge and then lifted out through the opening.

20 My raft is very light, so as to draw but a few inches of water, and the wheel I have also made so as to permit its use in very shallow streams. By this combination one of the objects sought for is accomplished. It permits 25 the use of the apparatus in streams where the ordinary devices of this kind would be useless

by reason of the lack of sufficient depth of water.

The wheel may be made to act in very slow stream by making it sufficiently large in diameter. 30

I claim—

1. The combination, with the raft floated by air-containing tubes, substantially as set forth, of the horizontal current-wheel and the pump, 35 and devices for conveying power from the wheel to the pump, substantially as specified.

2. The combination, with the raft having the opening B', of the wheel supported upon a vertical shaft located in said opening, and removable bearings for said shaft, substantially as specified. 40

3. The wheel C, consisting of the hinged vanes C³, and the open frame-work composed of the bands *c c*, hub-plates *c'* upon the wheel-45 shaft, vertical braces *c² c³*, and radial arms *c⁴* and *c⁵*, substantially as set forth.

ALEXANDER D. CLARKE.
